CLAIM

The ornamental design for a flight display screen or portion thereof with graphical user interface, as shown and described.

DESCRIPTION

FIG. 1 is a front view of a flight display screen or portion thereof with graphical user interface showing the new design; and,

FIG. 2 is a front view of FIG. 1, shown with a different broken line environment.

The outermost broken lines illustrate a flight display screen, which is the environment of the design, and which forms no part of the claimed design. The remaining broken lines, which make up portions of the graphical user interface, form no part of the claimed design.
